CLAIM

The ornamental design for a welding attachment for a respirator as shown and described.

DESCRIPTION

FIG. 1 is a perspective view showing the new design for a welding attachment for a respirator;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view showing the front component of the welding attachment for a respirator of FIG. 1 separately, to reveal aspects of the design that may not be apparent in other views;

FIG. 9 is a front view thereof;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is a perspective view showing the rear component of the welding attachment for a respirator of FIG. 1 separately, to reveal aspects of the design that may not be apparent in other views;

FIG. 16 is a front view thereof;

FIG. 17 is a rear view thereof;

FIG. 18 is a right side view thereof;

FIG. 19 is a left side view thereof;

FIG. 20 is a top view thereof;

FIG. 21 is a bottom view thereof; and,

FIG. 22 is a perspective view of the welding attachment for a respirator, in use on a respirator.

The broken lines in the drawings depict portions of the welding attachment for a respirator that form no part of the
